United States Patent Office

Des. 224,853
Patented Sept. 26, 1972

224,853

WIND CHIMES, OR SIMILAR ARTICLE

Rudi P. Meyer, Chicago, Ill., assignor to
Glovenmakers, Inc., Chicago, Ill.

Filed Jan. 12, 1972, Ser. No. 217,439

Term of patent 14 years

Int. Cl. D29—99

U.S. Cl. D72—1

FIG. 1 is a front elevational view of wind chimes showing my new design;

FIG. 2 is a side elevational view thereof with the ribbons omitted for convenience of illustration;

FIG. 3 is a top plan view of the design;

FIG. 4 is a bottom plan view; and

FIG. 5 is a cross-sectional view on the line 5—5 of FIG. 1.

I claim:

The ornamental design for wind chimes, or similar article, as shown and described.
